FIGURE 1 is a top perspective view of my new design of sled looking forward and down from the right side;

FIGURE 2 is a bottom perspective view of my new design of sled as would be seen with the sled of FIGURE 1 rotated about its longitudinal central axis;

FIGURE 3 is a right side elevational view of my new design of sled, the left side view being identical;

FIGURE 4 is a top plan view of my new design of sled;

FIGURE 5 is a bottom plan view of my new design of sled;

FIGURE 6 is a front elevational view of my new design of sled;

FIGURE 7 is a rear elevational view of my new design of sled;

FIGURE 8 is a right side elevational view of my new design of sled similar to that of FIGURE 3 but modified by the inclusion of two seats, the left side view being identical;

FIGURE 9 is a top plan view of my new design of sled which is shown in side elevation in FIGURE 8;

FIGURE 10 is a right side elevational view of my new design of sled similar to that of FIGURE 3 but modified by the addition of a windshield to the front cowl, the left side view being identical;

FIGURE 11 is a front elevational view of my new design of sled which is shown in side elevation in FIGURE 10;

FIGURE 12 is a top plan view of the front region of my new design of sled which is shown in side elevation in FIGURE 10;

FIGURE 13 is a right side elevational view of my new design of sled similar to that of FIGURE 3 but modified by the inclusion of rear cowl, the left side view being identical;

FIGURE 14 is a top plan view of my new design of sled which is shown in side elevation in FIGURE 13;

FIGURE 15 is a right side elevational view of my new design of sled similar to that of FIGURE 13 but modified by the inclusion of a seat, the left side view being identical; and

FIGURE 16 is a top plan view of my new design of sled which is shown in side elevation in FIGURE 15.

I claim:

The ornamental design for a sled, as shown and described.
